Arnold Zavell, New York, N. Y., assignor to The Fabricmart Corporation, New York, N. Y., a corporation of New York

Application April 28, 1949, Serial No. 2,318

Term of patent 3½ years

(Cl. D92—1)

To all whom it may concern:

Be it known that I, Arnold Zavell, a citizen of the United States, residing in the city of New York, in the county of New York and State of New York, have invented a new, original, and ornamental Design for a Textile Fabric, of which the following is a specification, reference being had to the accompanying drawing, forming part thereof.

The figure is a plan view of a textile fabric, showing my new design. The design unit is outlined by dotted lines and is repeated as indicated.

I claim:

The ornamental design for a textile fabric, substantially as shown and described.

ARNOLD ZAVELL.
